UNITED STATES PATENT OFFICE.

JOHN H. F. SHULZE, OF NEW YORK, N. Y.

RAILWAY-TRACK CONSTRUCTION.

No. 858,110.

Specification of Letters Patent.

Patented June 25, 1907.

Application filed March 20, 1907. Serial No. 363,377.

To all whom it may concern.

Be it known that I, JOHN H. F. SHULZE, a citizen of the United States, and a resident of the city of New York, Jamaica, borough of 5 Queens, in the county of Queens and State of New York, have invented a new and Improved Railway-Track Construction, of which the following is a full, clear, and exact description.

10 The purpose of this invention is the provision of a railway track of substantial build without the use of ties, and in which that side of the rail which is worn or otherwise damaged may be taken up and replaced without interfering with the opposite side thereof 15 or the traffic passing over the road.

To this end the preferred form of the invention consists of rails which are longitudinally divided on a central vertical plane. 20 The two sections of each rail thus formed are bolted or otherwise secured together, with the abutting ends of the alining sections breaking joint with those forming the opposite side of the rail. Each rail section is constructed with an extended base flange which is embedded in a road bed of concrete. This bed is assisted in maintaining the rails spaced to the proper gage, by transversely arranged tie-bars. 25

30 Reference is to be had to the accompanying drawings forming a part of this specification, in which similar characters of reference indicate corresponding parts in all the figures.

Figure 1 is a cross section through the preferred form of my invention, and Fig. 2 is a 35 plan of the same, partly in section.

In carrying out my invention, I employ rails 1—1, each of which is composed of two longitudinal sections 2—2 which, when 40 bolted or otherwise secured together, form a rail having heads and webs of the ordinary form. The dividing plane between the two sections of each rail, which is vertical, is preferably centrally located, forming both the outer and inner sections of the same size. 45 The base flanges 3 and 4, respectively, of both the inner and outer sections, are of extended width, with the inner flanges formed with downwardly-turned edges, as indicated at 5, which hold the rails against lateral displacement when embedded in a concrete road bed 6, as indicated in Fig. 1.

As shown in Fig. 2, the rail sections of each rail, when secured together, are placed so 55 that the abutting ends of two alining sections will break joint with the corresponding sec-

tions forming the opposite side of the rail. By this construction it is possible to remove either the inner or outer half of the rail without interfering with the other portion thereof, and thus avoid any interference with the traffic over the road while taking up and replacing worn or damaged rail sections. Moreover, since the head of the rail usually wears out at the inside of the track before the outside of the same is materially affected, it is possible by my invention to replace only that portion of the rail which is worn, leaving the opposite half intact.

For assisting the concrete road bed 6 in maintaining the rails spaced to the proper gage, the latter are connected together at the joint of each rail section and at other points if desired, by transverse tie-bars 7. These tie-bars as shown, are formed with a flat-faced head 8 at each end, which bears against the inner face of the rail web. Bolts 9 which connect the sections of each rail together, are also preferably utilized for securing the tie-bars 7. For this purpose the bolts 80 pass through the heads 8 as best shown at the sectional portion of Fig. 2. The flanges 3 and 4 of each rail are also connected together at the joints of alining sections, by plates 10 which are preferably bolted in place, each 85 flange being thickened at the point of application of the plate, as best shown in Fig. 1, in order to provide sufficient screw-threads for the bolting operation.

It is obvious that the construction hereinbefore described may be departed from in numerous particulars falling within the scope of the annexed claims.

Having thus described my invention I claim as new and desire to secure by Letters Patent:

1. A railway construction, comprising rails longitudinally divided on a vertical plane forming each into two sections with flat inner faces, each section of said rails having extended base flanges, with downwardly-turned edges formed on the flanges of the inner sections, tie-bars, unitary means for connecting the sections of each rail together and attaching said tie-bars, whereby the flat faces of opposed sections are forced into contact throughout, and plates connecting the base flanges of alining sections together where the sections break joint.

2. A railway construction, comprising rails longitudinally divided on a vertical plane forming each into two sections with

flat inner faces, said sections of each rail breaking joint with each other and provided with an extended base flange, means for connecting the opposed sections of each rail together, whereby the flat inner faces are forced into contact throughout, and plates bolted directly to the top of the base flanges of alining sections connecting the same together.

In testimony whereof I have signed my name to this specification in the presence of two subscribing witnesses.

JOHN H. F. SHULZE.
